ATTORNEY

UNITED STATES PATENT OFFICE.

WILLIAM SMITH, OF BOSTON, MASSACHUSETTS.

METAL CUTTER AND PUNCH.

SPECIFICATION forming part of Letters Patent No. 450,599, dated April 14, 1891.

Application filed August 30, 1890. Serial No. 363,565. (No model.)

To all whom it may concern:

Be it known that I, WILLIAM SMITH, a citizen of the United States, residing at the city of Boston, in the county of Suffolk and State 5 of Massachusetts, have invented a new and Improved Metal Cutter and Punch, of which the following is a specification.

The nature of my invention is that of a pair of metal shears supported on a platform 10 or a bench and operated by a handle which works above the upper shear-blade, which handle is supplemented by another handle working (from below the place of the meeting of the blades) also upon the upper blade, (by 15 means of appropriate connections,) with which is combined at the back part of the tool a punch, also worked by either the single handle or by the two handles combined; and the object is to furnish a device for cutting 20 metal plates of any width with a power graduated to the resistance offered, and with the same tool to punch in the plates holes of varying sizes.

In the drawings, Figure 1 is a side view of 25 my device. Fig. 2 is a view from the left-hand end of that part of Fig. 1. Figs. 3, 4, 5, and 6 are views in vertical section of some minor details of Fig. 1, and are hereinafter fully explained.

In the drawings, E, Fig. 1, is the platform 30 of the device, being a piece of board. (A bench or a shelf is sometimes used.)

F F F, Fig. 1, is the standard, being a slab 35 of iron, of shape as seen, placed on edge and fastened by braces and screws (one is seen at G, Fig. 1) to the platform E. The lower part of the standard at the left-hand end (see Fig. 1) is shaped into a geared segment of a circle whose center H^X is the point of rotation 40 of the horizontally-disposed bar H, Figs. 1 and 2, which bar is called the "lower-lever-holding bar," as its left-hand end is held by a pin passing horizontally through it and through the lower end of the "lower lever" J, Fig. 1, 45 which lever J is thus held by the pin K^X with the geared portion of a circle K (fitting to and gearing with the geared segment (already referred to, of the standard F, at its lower end, (see Figs. 1 and 2,) in gear with the said 50 standard-segment. This lower lever J is seen in Fig. 2 to be bent at the left-hand side of the standard F (in practice to the distance

of, say, two inches) and to proceed upward. This is in order that when the levers are in operation the lower lever shall not interfere 55 with the working of the upper lever, and in this case I sometimes, of course, remove the upper cutter-connecting bar V.

L, Fig. 1, is the "upper lever." This is made similarly to the lower lever, carrying a 60 similar geared portion of a circle M, Fig. 1, (I sometimes dispense with the geared arrangement and use a simple pin and a cam,) and is borne by two curved bars of iron, (one is seen in Fig. 1, N,) called the "upper-lever 65 holder," which latter is firmly fastened to and held by the "upper cutter-bar" P, Fig. 1, to the extreme (left-hand) end of which it is attached. This upper cutter-bar is flush with the face of the standard F on the farther side, 70 and on the hither side at the right hand has a piece of iron P^X of the same thickness with the cutter-bar, welded to it, (see Fig. 1,) by means of which the cutter-bar partially rotates on the "bearing-pin" Q, Fig. 1, which 75 pin is borne by the standard F on the farther side and on the hither side by the "upper cutter-brace" R, Fig. 1. (See also Fig. 5.)

S, Figs. 1 and 5, is called the "pressure-pin," and is a pin fastened to the standard F and 80 protruding through a curved slot in the bar P, the slot in the bar P moving on it loosely. The function of this pin is to fortify the bearing-pin Q against any fortuitous extra strain in cutting thick iron. The upper cutter-bar 85 carries the "upper cutter-blade" T, Fig. 1, (and Fig. 4,) which is fastened to it by screws, as seen in Fig. 1. The "lower cutter-blade" U, Fig. 1, is similarly screwed to the standard F. 90

V, Fig. 1, is a bar called the "upper-cutter-connecting bar," which is attached by a pin to the upper cutter-bar P, near to the left-hand end of the latter. At its lower end the bar V is attached to the pin K^X, on which it 95 plays loosely. (See Fig. 2.)

W, Figs. 1 and 3, is the "strengthening-bar," and is attached at its lower end to the lower part of the standard F, near the left-hand end of the same, and at its upper end to 100 the upper arm of the standard F. The function of this bar W is to connect the upper and lower arms of the standard F, and thus to counteract the effect upon the arms of any

excessive strain. I sometimes fasten this strengthening-bar W with two screws and nuts on the farther side of the device, thus facilitating the temporary removal of the bar 5 when a very wide sheet of metal is to be operated on.

The appliances already described are for cutting sheets or bars of metal. I am now to describe the apparatus of my device for punching holes in iron, &c.

$X X$, Fig. 1, is the hither side of a frame of two similar pieces of thick sheet-iron, set up edgewise, of shape as seen, and fastened by three (more or less) screws to the upper arm 15 of the standard F . A space is cut away (as seen) at the point Y , which, when the tool is in use, admits the insertion horizontally of the metal into which a hole is to be punched. Between the two sides $X X$, as seen in horizontal section in Fig. 6 and in vertical section in Fig. 4 of the frame, and supported as seen in Fig. 4, is a block of metal Z , perforated in the center, as seen in Fig. 4, and called "the die." Above the open space Y , Fig. 1, 25 is seen at the left-hand side a rounded protuberance B^x , shown in the horizontal cross-section view of Fig. 6 to form nearly a full circle. This is of iron and bears (see dashed lines in Fig. 6) a hole A^x , running perpendicularly, as seen in dashed lines in Fig. 1, to 30 within a short distance from the top of the cylindrical block B^x . This hole bears the punch, which is not represented, and is held in place in any convenient manner—say by a 35 set-screw running through the side or the top of the block B^x . This block B^x is seen in Fig. 6 to be joined at its right-hand side to a slab of metal C^x , fitting tightly, but so as to admit of motion up and down between the 40 two sides of the frame $X X$. The right-hand half of this slab C^x is continued downward as far as the dotted horizontal line in the drawings, Fig. 1, and forms a piston or 45 plunger E^x , and is kept in place by the metallic slab, forming the "plunger-cover" D^x , Figs. 1 and 6, which cover is screwed to the two respective edges of the frame $X X$, as shown in Figs. 1 and 6. In the hither and farther sides, respectively, of the frame $X X$ 50 is a slot at the center of the plunger E^x . Through these slots runs horizontally a pin F^x , Fig. 1, passing to the outside of the frame $X X$ on each side and moving loosely in the slot. This pin F^x passes through and is firmly 55 attached to the plunger E^x . To this pin F^x is loosely attached a bar G^x , Fig. 1, called the "plunger-bar." The lower end of this plunger-bar is similarly attached to the upper cutter-bar P .

Operation: The substance to be cut is placed 60 between the two cutter-blades in the usual manner, and by drawing down the upper end of the upper lever L the upper cutter-blade T descends and performs the cutting. When an unusually thick piece of metal is to be cut, 65 the lower lever J is also used, the upper cutter-connecting bar V assisting in drawing down the upper cutter-bar P . In punching holes in metal sheets or slabs the article to be punched is inserted in the open space Y , and, 70 by the action of the lever L or of both levers, the plunger-bar G^x is carried by the upper cutter-bar P downward, bearing with it the plunger E^x and the block B^x with the punch-tool, (not represented,) the lower end of which 75 punch-tool effects the required perforation of the piece of metal operated on.

I claim—

1. The combination and arrangement of the standard and the stationary and moving cutting-blades and one or more working-levers with the punching device actuated by the same lever or levers, all substantially as shown and described.

2. The combination and arrangement of the standard, the stationary and moving cutting-blades, and the lever operated above the upper cutting-blade, all substantially as described and shown.

3. The combination and arrangement of the standard and the two cutting-blades and the upper lever, with the subsidiary lower lever and the upper-cutter-connecting bar, all substantially as described and shown.

4. The combination, with the standard and two cutting-blades, the upper blade being actuated by a lever above it, of the strengthening-bar W , attached, respectively, to the two opposing portions of the standard, all constructed and arranged substantially as shown and described.

5. The combination, with the moving half of the cutting-shears, of the bearing-pin Q and the pressure-pin S , with the slot shown in the moving blade P , all substantially as described and shown.

6. The combination and arrangement of the standard; the two cutting-blades, and the upper lever with the upper-lever holder N , composed of two metallic bars fastened to the upper cutter-bar P , all constructed and arranged substantially as shown and described.

WILLIAM SMITH.
